SLIDE LOOP

Carl E. Anderson, East Orange, N. J.

Application January 18, 1934, Serial No. 707,044

4 Claims. (Cl. 24—196)

This invention relates to an improved slide loop for holding straps on apparel or in other uses at which adjustability is desirable.

The invention also resides in an improved method of making such slide loops to provide the new article.

The object of the invention is to provide a buckle or slide which holds a strap against any side movement or bunching whatsoever which in 10 turn avoids any canting of the article on the strap. Furthermore, the cross-arm or bar of the loop is materially strengthened by a novel construction of its edge which is the portion that provides the improved gripping and spreading portion of the 15 article.

The invention is illustrated in the accompanying drawing in which Figure 1 is a front view of our improved slide loop with a strap threaded through it. Figure 2 is a rear view of Figure 1. Figure 3 is a rear view with the end of the strap 20 released to show part of the cross-bar. Figure 4 is a section on line 4—4 of Figure 1 without the strap. Figure 5 is a section on line 5—5 in Figure 1 with the strap shown by dotted lines. Figure 6 is a section on line 6—6 in Figure 1, showing the flange on the cross-bar and the corrugation on 25 the flange parallel with its direction of extension. Figure 7 is a perspective view of a fragment of the slide loop showing part of the frame and the lower part of the cross-bar. Figure 8 is a view similar 30 to Figure 6 showing part of the frame and the lower part of the cross-bar.

It has been customary in loops of this kind to 35 form teeth for gripping the strap at the cross-bar by forming teeth on the bottom edge by slitting or punching the teeth back. This form of tooth presents only one corrugated or toothed edge for engaging the strap.

The improvement in this case lies in the formation 40 of teeth in the form of a corrugated flange which corrugations extend from front to rear to form teeth on both the front and edges of the flange, that is, on the front and rear of the cross-bar.

45 The slide loop is formed of a frame and a cross-bar. The frame is formed of wire and is rectangular or oblong, consisting of a top strand 10, end strands 11 and 12 and a bottom strand 13. In a button loop the bottom strand is looped as at 50 14 to receive the shank of a button. The end strands 11 and 12 inset toward each other as at 15.

The cross bar 16 has a central slot 17 for the 55 reception of the strap. The cross-bar has its ends 18 looped around the inset parts 15 of the

end strands 11 and 12. The looped ends 18 are approximately as wide as the inset parts and this prevents any sliding of the cross-bar on the frame, even under excess strain.

The cross-bar has a flange 19 at its top edge, the flange being bent back and extending between the inset portions 15 to brace them against inward movement and to form a better gripping edge for the strap a.

The lower edge of the cross-bar is also flanged by our new method. The flange is shown as comprising a central part 20 and teeth 21 that flank the central part although it will be evident that the teeth may extend all the way across if desired.

10 The teeth and the flange are formed by forcing the metal downward through a die, an extending method as defined from a stamping or bending method. The new method of making the teeth provides a tooth that extends from front to back 15 of the flange.

15 In other words, the teeth or corrugations extend from front to back of the flange, providing toothed engaging edges at 22 and 23, see Figure 4 where the strap turns and also a corrugated space 20 in between 22 and 23. These corrugations not only hold the strap a against slipping but also prevent the strap from sliding sideways or bunching at either end or the center. This insures an even pull on the strap all the way across 25 as well as an even strain on all parts of the slide.

20 In the case of a button loop the central part 20 of the flange is arched to provide clearance for the insertion or removal of a button from the 30 button loop 14.

25 The modification shown in Figure 8 provides an extended flanged part with teeth 21 notched at the back edge as at 24 to provide additional gripping edges. The use of this form is optional although in heavy forms of loops as used on trunk 35 straps or other heavy straps they may be desirable.

The size and proportions of the parts may be 40 varied without departing from the scope of my invention.

I claim:

1. A slide loop comprising a frame with end bars off-set slightly inwardly, a flat cross-bar embracing said off-set portions and thereby prevented from sliding and having its bottom edge provided with a corrugated flange extending transversely relative to said bar to provide a gripping and spreading portion for a strap.

2. A slide loop comprising a rectangular frame of wire with end strands inset at opposite points 50 55

and a flat metal bar coiled at its ends around the inset portions and thereby prevented from sliding, the bar having a projecting flange at its bottom edge, the flange having an arched central portion and corrugations flanking the central portion.

5 3. A slide loop comprising a rectangular frame of wire with end strands inset at opposite points and a flat metal bar coiled at its ends around the inset portion and thereby prevented from sliding, the bar having a projecting flange at its bottom edge, the flange having an arched central por-

tion and corrugations flanking the central portion, the frame having an open depressed part to form a button loop below the arched portion of the bar.

4. A slide loop comprising a frame, the frame including top and bottom bars, a cross bar secured to the ends of the frame, one of the bars having a flange projecting laterally from one edge, the flange having corrugations parallel with its direction of extension and having a straight outer edge.

10 C. E. ANDERSON.
